UNITED STATES PATENT OFFICE.

JOSEPH J. WEYER, OF CHICAGO, ILLINOIS.

DESIGN FOR A LAMP.

No. 38,638.

Specification for Design.

Patented June 25, 1907.

Application filed May 27, 1907. Serial No. 376,028. Term of patent 7 years.

To all whom it may concern:

Be it known that I, JOSEPH J. WEYER, a citizen of the United States, residing at Chicago, in the county of Cook and State of Illinois, have invented a new, original, and ornamental Design for Lamps, of which the following is a specification, reference being had to the accompanying drawing, forming a part thereof.

The figure is a perspective view of a lamp, showing my new design.

I claim:

The ornamental design for a lamp, as shown.

JOSEPH J. WEYER.

In presence of—

RALPH A. SCHAEFER,
CHAS. E. GAYLORD.
